UNITED STATES PATENT OFFICE.

WILLIAM E. HOPKINS, OF PITTSBURGH, PENNSYLVANIA.

NON-REFILLABLE CIGAR-BOX.

1,093,855.

Specification of Letters Patent.

Patented Apr. 21, 1914.

Application filed April 19, 1912. Serial No. 691,935.

To all whom it may concern:

Be it known that I, WILLIAM E. HOPKINS, a citizen of the United States, residing at Pittsburgh, in the county of Allegheny and 5 State of Pennsylvania, have invented certain new and useful Improvements in Non-Refillable Cigar-Boxes; and I do declare the following to be a full, clear, and exact description of the invention, such as will enable others skilled in the art to which it 10 pertains to make and use the same, reference being had to the accompanying drawings, and to the letters and figures of reference marked thereon, which form a part of this 15 specification.

This invention relates to an improved non-refillable cigar box with stamp destroyer.

The object of the invention is to provide a cigar box that will necessitate the destruction 20 of certain parts of the same before the superimposed layers of cigars may be removed therefrom, thereby preventing fraudulent use of the box, such as refilling with the same or another brand of cigars, and the 25 invention further consists in the certain details of construction and combination of parts, as will be fully described hereinafter.

In the accompanying drawings;—Figure 1 is a sectional perspective view of a portion 30 of one end of a cigar box showing the internal arrangement. Fig. 2 is a similar view of the opposite end of the box. Fig. 3 is a perspective view of one end of one of the metallic strips used for attaching the tape 35 or ribbons to the inner side walls of the box, for the purpose of securing interposed sheets of paper. Fig. 4 is a similar view of the reverse side of said strip. Fig. 5 is a reduced perspective view of the folded 40 paper interposed between the layers of cigars, showing the arrangement of the several ribbons therethrough. Fig. 6 is a sectional view of a portion of the box showing the stamp destroyer attached in 45 position. Fig. 7 is a perspective view of said destroyer. Fig. 8 is a face view of a modified form of stamp destroyer used in connection with bottles requiring revenue 50 stamps. Fig. 9 is an enlarged sectional elevation of a portion of the stamp destroyer showing the construction of the bars.

To put my invention into practice and thereby provide a cigar box that cannot be refilled without detection, I first form a box 55 1, of a suitable size, the bottom of which is formed with a tongue 2, about its four edges,

which fits neatly in grooves provided in the side and end walls, the said sides and ends having a groove 3, located about the middle of their width, thus weakening these parts 60 that the box may be easily destroyed. The box is fitted with a lid 4, and tacked together in the usual manner.

To prevent the removal of the first layer of cigars 9 without detection, I thread or 65 weave two or more sets of double ribbons 8' about the same, if in two sets said ribbons are located near the ends of the cigars, and if three sets are used, one set would be woven about the middle of the cigars. The 70 free ends of these ribbons are attached to the bottom of the box at the end of the row of cigars, either by the use of an adhesive material or small tacks.

It will be seen that when the first layer of 75 cigars are secured in this manner, it will be impossible to remove the cigars intact without first removing or cutting several of the interwoven ribbons.

Placed upon the top of the second layer of 80 cigars is a folded sheet of paper 10, the inner surface being gummed, and having arranged within the fold, several ribbons 13, extending in the direction of the length of said paper and a transverse ribbon 11 located at 85 the center and beneath the first mentioned ribbons 13. The ends of the transverse ribbon 11 terminate in recesses 12 formed in the folded paper 10 and are used to remove and destroy the same. The free ends of the 90 longitudinal ribbons are attached to the end walls of the box by the use of metallic strips 14, having integral barbs 16, said barbs being punched from angular cuts 15 and bent into form. These metallic strips 14 are at 95 attached to the end walls of the box by means of a suitable tool, made for that purpose, and engage with and hold the longitudinal ribbons 13 rigidly.

To remove the second layer of cigars it is 100 necessary to remove the folded sheet 10 upon the top of the same. This may be done by grasping the free ends of the transverse ribbon 11, and with an upward pull break the longitudinal ribbons 13, and at the same 105 time destroy the folded paper 10. This folded paper 10, being gummed on its inner face is first moistened and pressed together before being placed in position in the box, thereby cementing the several ribbons permanently in place. A similar folded sheet 110 is placed upon each of the several superim-

posed layers of cigars, and must be destroyed before the cigars are removed.

By means of the above-described arrangement it is obvious that the cigars cannot be removed without detection, thereby affording protection to the manufacturer and to the general public.

To provide a stamp destroying device in connection with the above-described box, I 10 form from thin metal a plate 5, adapted to be attached to the lid and front wall of the box, by means of integral barbs 6, as at Fig. 1, or by the use of tacks 6', as at Fig. 6. This plate is formed with a barbed surface 15 7, formed by a multiplicity of small punch openings, the construction of which will be best seen at Fig. 9, of the drawings.

The revenue stamp (not shown), is placed over the rough surface of the plate 5, and 20 when pressed down, will be perforated by a multiplicity of small openings, thereby destroying said stamp. It will be seen that, by reason of the number of openings formed in the stamp it could not be removed intact, 25 but would come off in pieces.

At Fig. 8, of the drawings, I have shown a modified form of the stamp destroyer for use upon the necks of bottles. This form comprises a body-portion having the roughened surface 7 and at either end are transverse extensions 17, each provided with a slot 19 and tongue 18. This plate is bent over the cork of the bottle and the extensions 17 30 about the neck of the same, and there fastened by means of the tongues 18 inserted in the slots 19, and locked by a reverse bend of said tongues.

It is obvious that the box as herein described may be used for packing various

kinds of goods. Therefore I do not wish to 40 confine myself to cigar boxes alone, as the invention is applicable to other boxes.

The box is made of frail material, such as thin wood, and few tacks or brads used in its construction. The bottom of the box, 45 depends wholly upon the tongue and groove connection 2 and the interwoven ribbons 8, 8', for maintaining its position, and should said ribbons be cut to remove the cigars, the sides and ends of the box would spring out- 50 wardly to release said bottom, thereby destroying the usefulness of said box.

Having thus described my invention, I claim:—

1. In combination with a box, a double 55 sheet of paper interposed between each successive layers of goods, a series of longitudinally-arranged ribbons within the fold of said sheets, a means of attaching the ends of said ribbons to the inside walls of the box, 60 and a transverse ribbon arranged within the fold of the paper and beneath the longitudinally-arranged ribbons.

2. In combination with a box, a double sheet of paper arranged between each successive layers of goods, the one sheet cemented to the other, a series of longitudinally-arranged ribbons within the fold of said sheets, and a means comprising metallic strips having barbs for attachment with the 70 free ends of the longitudinal ribbons and with the inner walls of the box.

In testimony whereof, I affix my signature, in presence of two witnesses.

WILLIAM E. HOPKINS.
